PROCESS OF CRACKING MINERAL OIL.

Application filed January 25, 1926. Serial No. 33,437.

In the art of treating high boiling and high gravity hydrocarbon oils for the purpose of decomposing them to convert them into lower boiling and lower gravity hydrocarbon oils, 5 which art is generally known as "cracking", the most common procedure is to subject the oil to be cracked to high temperature and a substantial pressure above atmospheric. The art is a very old one. In recent years, its most 10 useful industrial application is in the production of gasoline from such higher boiling and higher gravity petroleum oils as gas oil and fuel oils. The cracking operation may be conducted in batch or it may be carried on

15 in a continuous manner. The cracking may be effected in vapor phase or in liquid phase or partly in one phase and partly in another. With a sufficiently high temperature (the minimum of which is about 600° F.), and under a pressure of several atmospheres, a considerable percentage of, for example, gas oil, 20 may be decomposed or cracked into gasoline. At 800° and higher temperatures, under the moderate pressures specified, the conversion 25 will take place largely in vapor phase, or in both phases. If the pressure be greatly increased, a larger proportion of the oil will be cracked in liquid phase. At a pressure of (say) 600 pounds to the square inch or (say) 30 40 atmospheres, the oil will be cracked almost wholly in liquid phase.

In continuous processes for cracking higher boiling petroleum constituents to gasoline, it is old and well known to convey the oil 35 to be decomposed, which may be initially pre-heated, through a long tube or tubes in immediate contact with heating gases and therein to raise the oil to a cracking temperature and either complete the cracking therein or perhaps 40 form a part of the cracking therein. In the latter case, the partly cracked oil may be conveyed to a container or reaction chamber of relatively large cross-section, wherein the pressure is maintained, and wherein the temperature of the oil falls somewhat, although 45 not below an effective cracking temperature. In this chamber the cracking is completed and the oil will be relatively quiescent to allow deposition of the coke which is formed under 50 the high temperature conditions. Such proc-

esses have been carried on in vapor phase, in mixed phase and in liquid phase. In the liquid phase process, the oil may be allowed to escape through a loaded valve into a vaporizer, wherein there is maintained a pressure 55 but little above atmospheric. After passing the valve, the most of the oil immediately vaporizes. The vapors are fractionated and condensed. In the vapor phase process, the cracked, or partially cracked, vapor is taken 60 off from the container and goes either direct to a condenser, or through a fractionating tower in which a product of the desired boiling point is separated out.

In such processes the formation of carbon 65 and resinous matters gives rise to serious difficulties. It is desirable, for various reasons, especially in liquid phase processes, to effect all the cracking in the tubes, but the formation and accumulation of coke in the tubes 70 tends to insulate the oil from the heating gases and clog the tubes, necessitating their frequent cleaning. The process is therefore uneconomical if not commercially impracticable. If only part of the oil is cracked in 75 the tubes and if the partly cracked oil is conveyed from the tubes to a large reaction chamber, in which the cracking is completed, as explained above, the trouble is merely ameliorated, in that some of the coke that would 80 otherwise form or deposit in the tubes forms or deposits in the large reaction chamber. The tubes nevertheless become lined or choked with carbon, and while they need to be cleaned less frequently, they must be cleaned 85 at intervals, and frequent cleaning of the reaction chamber is necessary, and the process is more economical and practicable only in degree.

The ideal liquid phase process is one where- 90 in the oil is subjected to the cracking operation and is completely cracked while traveling along a long thin stream, from which it continuously escapes into an expansion chamber wherein most of it immediately vaporizes, 95 the gasoline being separated, fractionated and condensed and purified by known methods. The object of this invention is to provide a practicable process of this character.

Before describing the process it may be 100

informative to set forth more in detail the cause, nature and effects of coke formation. Certain factors in the problem are well understood, while other factors seem not to be generally appreciated and may not have been heretofore known.

With the usual method of heating the oil to raise it to a cracking temperature, whether it is flowing in a long tube or comparatively quiescent in a tank, the temperature difference between the furnace gases and the oil is and must be very great. Consequently the film of oil immediately in contact with the metal of the tube is raised to a temperature much above that of the average temperature of the whole body of oil. This causes the highly heated part of the oil to be raised not only to a decomposition or cracking temperature but to a temperature high enough to separate out certain constituents and convert them into coke, which is deposited on the tube wall. Substantial deposition of coke does not occur until after the process has been in operation for some little time. Once, however, the coke starts to form, it forms very rapidly. The coke acts as an insulator, requiring more heat to penetrate it in order to heat the entire body of oil to a cracking temperature. This raises the temperature of the tubes. The coke that has already formed acts to absorb oil, which, at the increased temperature of the tubes, causes it to form coke rapidly. In short, once the formation of the coke starts, its rate of production is constantly accelerated.

Careful experimental work in connection with the practical development of the present invention, wherein the oil was heated to a cracking temperature under conditions which prevented local heating much above the upper limit of the desirable cracking temperature, resulted in the formation of little or no coke. That is, coke occurs within temperature ranges that are materially above the upper limit of the desirable cracking temperature zone. In the ordinary cracking processes, the oil flowing through the tubes is necessarily subjected to an excessively high temperature because the heat transfer from gases of combustion to the oil is very low and, in a commercial unit, it is essential that the difference in temperature between the heating gases and the oil be very great; otherwise, the large amount of heating surface necessary would involve too high a cost. Further, the insulating effect of the accumulating layer of carbon in the tubes necessitates a still greater temperature difference between the furnace gases and the tubes and the subjection of the peripheral zone of the stream of oil to still higher temperatures in order that the main body of the traveling oil shall be subjected to the lower cracking temperature desired.

However, while, in said experimental and development work, the oil was cracked without

substantial formation of coke, asphaltene was formed in substantial amounts. Asphaltene is often mistaken for coke and, like coke, it has insulating qualities and, its formation, when started, proceeds at an accelerating rate. Asphaltene, however, unlike coke, is soluble in different liquids, such as carbon bisulphide, or in petrolene, which latter substance itself may be separated out of asphalt by dissolving the asphaltene in gasoline, precipitating the asphaltene and evaporating the gasoline from the petrolene. Coke that is formed at higher temperatures cannot be dissolved and must be removed from the tubes by mechanical means.

It is clear that if the temperature difference between the heating medium and the oil could be economically reduced, the conditions propulsive of the formation of coke would be eliminated. It is also clear that even if the temperature of the heating medium could not be held below a point at which asphaltene will form, and that if the asphaltene remains behind and accumulates in the tubes, the latter could be cleaned expeditiously and economically by simply running through the tubes, at convenient intervals, a solvent of the asphaltene.

We have found it to be practicable to secure the desired low temperature difference between the heating medium and the oil by means of the indirect application of the primary heating agent and the direct transmissions of heat to the oil by means of a secondary heating agent which, under practicable absolute pressures, will boil at a temperature to which it is desirable to raise the oil, and which, in its vapor form, is flowed into heat exchange relation with the oil and is condensed thereby and gives up its latent heat to the oil, the condensate returning to a liquid body of the substance, which is continuously being heated by the primary heating agent and is continuously generating vapor. In the application of Pew & Thomas, No. 13,040, filed March 5, 1925, which is a continuation in part of an application filed March 17, 1924, No. 699,615, the advantage of using a vaporized metal, such as mercury, as a direct heating agent for mineral oil, is clearly and fully disclosed. Mercury has a high boiling point and high heat conductivity; it will not oxidize or disintegrate when heated or brought into contact with iron; and it may be condensed and its latent heat transferred to the oil by heat exchange at temperatures within the desirable zone of oil cracking temperatures. The most important and valuable quality of mercury vapor, in its application to the cracking of oil, is that, to accomplish the same degree and rapidity of cracking, the difference between the temperature of the mercury vapor and that to which it is necessary to raise the oil need be very small relatively to the necessary tem-

perature difference between the oil and ordinary furnace gases or other ordinary heating media. In other words, the temperature of the heating medium from which heat is 5 directly transferred through the tube wall to the oil may be so relatively low that all the objectionable coke forming conditions hereinbefore recited are minimized or avoided. No hard, insoluble, coky or resinous residue is 10 formed because of the absence of the elevated temperature required to form it; and the conditions promotive of the building up of an insulating wall of coke between the direct heating medium and the oil are absent. 15 However, even at the much lower temperature of the heating medium, asphaltene starts to form after the process has been in operation for some time; but at any time after it starts to form, the oil cracking process may 20 be interrupted for a few minutes, and the asphaltene may be readily removed by flowing a stream of solvent liquid through the tubes. Other positive advantages are herein- 25 after enumerated, as they may be more readily appreciated after the process is fully described.

In heating oil by means of furnace gases applied direct to a stream of oil flowing through a tube, a great temperature difference 30 between the furnace gases and the oil is not objectionable while the oil is being heated up to a cracking temperature. Below about 600° F., heat can be applied to the oil at a comparatively high rate per square foot 35 of heating surface without injurious local cracking. It is therefore found practicable to utilize the waste heat of the primary heating medium by subjecting the relatively cold oil to the heat of the furnace gases after they 40 pass beyond the mercury boiler, thereby quickly preheating the oil to a high temperature, which, however, preferably does not reach, and ought not to exceed, the temperature at which substantial cracking begins.

It is desirable, particularly after the oil 45 has been raised to a cracking temperature, to raise the temperature gradually through the cracking zone. While the higher the temperature, the more rapid the cracking, and 50 while it is permissible to impart a higher temperature to the oil with mercury vapor as a heating medium than with the usual furnace gases, due to the small temperature difference necessary between the oil and the 55 heating medium, it is objectionable, for reasons hereinbefore fully stated, to crack at an unnecessarily high temperature. While it is usually not necessary to exceed a temperature of about 875° at the exit end of the oil stream, 60 by our method this temperature can readily be raised in cases where the oils being handled demanded this increased temperature. A mercury vapor temperature 25° to 50° above that of the maximum temperature of 65 the oil, is capable of raising the preheated

part of the oil stream to the specified maximum temperature and it is practical to subject the entire stream of oil to the temperature of the mercury vapor immediately after the oil leaves the preheater. It is advantageous, however, to maintain a small temperature difference between the oil entering the stream and the mercury vapor, so as to avoid a sudden rise of temperature of the 70 peripheral part of the stream, or the film adjacent the inner wall of the tube. To maintain this small temperature difference and to insure a gradual heating up through the cracking range of the entire body of the oil and to provide a minimum practicable temperature difference between the mercury and the oil at all points in the latter's flow, it is arranged to heat the oil in stages, the temperature of the mercury being raised in the successive stages. 75

Other advantageous features of the process will be brought out in the following description.

While the process is not dependent for its execution on any particular construction and arrangement of apparatus, the drawings represent the lay-out of a plant in which the process is adapted to be carried out in a particularly practicable and advantageous way. 80

Fig. 1 is an elevation, largely diagrammatic, 85 of a complete cracking plant.

Fig. 2 is a detail view of one of the heat-exchange or cracking units.

The mercury boiler *a* is contained in a furnace *b* which is provided with a down-take *c*. The furnace gases pass upward around the boiler, thence laterally and thence downward through the down-take *c* and thence upward through a stack *d*. 95

Above the boiler is arranged a series of cracking units, each comprising a shell *e*, 100 functioning as an oil heating and mercury vapor-condensing chamber, and a nest of tubes *f*. The tubes are so arranged that the oil entering from pipe *g* must flow back and forth repeatedly before leaving at *h*. It is desirable that the oil should be given sufficient velocity to aid in cleaning the tube walls and the length of travel must be sufficient to allow proper time for the reaction to take 105 place. 110

From the mercury boiler *a* a mercury vapor line *i* extends upward and thence laterally along the cracking units 1, 2, 3 and 4, and is provided with four feeds 11, 12, 13 and 14 extending to the respective chambers *e* of the four cracking units 1, 2, 3 and 4. Each feed is provided with a valve *j*. 115

From the several chambers *e* extend mercury condensate return lines 21, 22, 23 and 120 24 to a header *p*. Each return line comprises a trap consisting of a cup *k* and a goose-neck *m*, and another goose-neck *n*. The upper part of goose-neck *m* connects with the upper part of the cup by a vapor pipe *o*. The part 125 130

n connects with a header *p*, which is connected with the mercury boiler by means of a pipe *r*.

In the down-take *c* is a nest of tubes *s* comprising a preheater. Relatively cold oil is pumped into one of the bottom tubes and thence flows back and forth repeatedly and finally leaves one of the top tubes and flows through pipe *g* to cracking unit 1. The oil leaving the tubes *f* of unit 1 through pipe *h* enters unit 2, and thence flows through units 2, 3 and 4 in series.

The mercury vaporized in boiler *a* passes through line *i* and thence, through the independent feeds 11, 12, 13 and 14, to the several mercury chambers *e* of the four units 1, 2, 3 and 4.

In each chamber *e* the mercury vapor is condensed and its latent heat is transferred to the oil. Mercury condensate returns from the chambers *e* through the return lines 21, 22, 23 and 24 to the header *p* and thence, through pipe *r* to the boiler *a*.

From the last cracking unit 4, the oil passes through a pipe *h* into a vaporizer *v*. The inlet to the vaporizer may be controlled by a valve *u*. Beyond the vaporizer is a bubble tower *w* and beyond that a condenser *x*.

A more specific description of the operation follows: It should be understood that the more detailed information, such as pressures and temperatures, are illustrative only. The figures given are to be taken in a relative, rather than in an absolute, sense. Various pressures, temperatures and temperature differences may be desired by the operator, and these may be predetermined with a rather close approach to exactitude.

It should be particularly borne in mind that the specific plant above described is adapted particularly to cracking mainly in a liquid phase, as the pressure in the oil system given below indicates.

Oil is pumped through the preheater *s* and thence in series through the tubes *f* of the cracking units and is maintained, throughout, at a high pressure, say 600 pounds per square inch.

The mercury boiler may be operated at a pressure of about 80-85 pounds gauge pressure, which will give a mercury vapor temperature of about 900° F. The mercury vapor flows through the several cracking units in parallel.

The temperatures of the mercury chambers *e* of the successive units should progressively increase. The valve in line 14 controlling the inflow of mercury vapor to unit 4 is left wide open, which will maintain a temperature in chamber *e* of that unit of 900° F. A lower temperature may be established in any chamber by more or less throttling the admission valve. Thus the valve in line 13 is closed to the degree that will give a temperature in the chamber *e* of unit 3 of 850° F. Chamber *e* of unit 2 may be held at a tem-

perature of 800° F. by still further throttling the valve in line 12. By still more nearly closing the valve in line 11, chamber *e* of unit 1 may be held at a temperature of 750° F.

The oil entering the preheater *s* may have a temperature of 200° F., and during its flow therethrough is heated to any desired higher temperature, say 600° F. It is desirable that the oil should be heated in the preheater to a temperature below that at which substantial cracking occurs. Indeed it is preferred that there shall be no cracking at all in the preheater. The oil then enters the tubes *f* of unit 1 at a temperature of 600° F. By heat exchange with the mercury vapor in the surrounding chamber *e*, (which as above stated, is at a temperature of about 150° F.) the vapor is condensed and its latent heat is transferred to the oil, which leaves unit 1 at a temperature of 670° F. There is thus an average temperature difference between the heating medium and the heated medium of about 115° F.

The oil enters unit 2 at a temperature of 670° F. and is heated therein to a temperature of 740° F. There is thus an average temperature difference in this unit between the mercury and the oil of 95° F.

The oil enters unit 3 at a temperature of 740° F. and leaves at a temperature of 810° F., the average temperature difference in this unit between the mercury and oil being 75° F.

The oil enters unit 4 at a temperature of 810° F. and leaves at a temperature of 875° F. The temperature difference between the mercury and oil in this unit is 57° F.

The oil leaving pipe *h* at valve *u* enters the vaporizer *v*. Here the pressure on the oil is instantly released and nearly all of it immediately vaporizes. A small proportion (say five or ten percent) is thrown down in the vaporizer. The vapors enter the bubble tower *w* wherein they are fractionated by passing up through descending condensed oil. The uncondensed gasoline vapors leave the bubble tower and are subsequently condensed in condenser *x*. The gasoline vapors may be purified on the way to the condenser or the final condensate may be purified.

The small temperature differences between the heating medium and the oil in the several cracking units, and the relatively low absolute temperature of the heating medium, are important features of the process. Under these conditions, there can be little, if any, localized overheating of the oil and hence little, if any, formation or deposit of carbon. Establishment of quite definite predetermined temperatures is also much facilitated.

The mercury that is condensed in the chambers *e* of the several cracking units is returned by gravity to the boiler. In order to effect this gravity flow, the units should be

located at such a height above the boiler that the column of mercury in the return line may have a head equal to the pressure carried in the boiler.

8 Any foreign matter in the mercury collects in the traps *km*, and is thus prevented from being carried back into the boiler. From time to time the traps may be opened and foreign matter removed from the surfaces of the 10 mercury in the cups *k*.

A by-pass for excess mercury vapor is provided between the mercury vapor line *i* and the liquid mercury return line *r*. In this by-pass is located a safety valve, or maximum 15 pressure relief valve *y* and a condenser *z*.

A longitudinal section of one of the cracking units is shown in Figure 2. The shell *e* must be made of sufficient strength to carry the required pressure of mercury vapor.

20 The tubes *f* must be made of a size and strength suitable for carrying oil at the high pressure specified. For the liquid phase system, the tubes should have walls about half an inch thick. The tubes may be welded to 25 the heads of the shell *e*. By reason of the temperature difference between the tubes and the shell, provision should be made for expansion and contraction. One way of providing for expansion and contraction is to

30 make the shell in two sections with an expansion joint *e'* at the center. These details, however, may be worked out by engineers skilled in the art of heat exchanging.

The process is also adapted to be modified 35 to effect the cracking of the oil in vapor phase or, more conveniently, in a two phase (liquid and vapor phase) process. Such a process is set forth and specifically claimed in another application filed by us February 24, 1926, Serial No. 90,247.

In the cracking system described, due to the prevention of localized heating of the oil substantially above the highest predetermined cracking temperature, no part of the

40 oil reaches the temperature at which coking takes place. There is ultimately some formation of asphaltene, which, at moderately high temperatures, is formed before the production of coke at still higher temperatures, as hereinbefore explained. At any time after asphaltene starts to form and deposit on the tubes, a solvent may be pumped through the oil system, which dissolves the asphaltene and thus cleans out the tubes. This method 45 of cleaning out the tubes, wholly unworkable to clean out coke deposits and therefore inapplicable to other systems of cracking, is obviously strikingly simple, expedient and economical.

50 The main advantages of the process above described may be enumerated as follows:

Little or no heat is wasted in coke formation and no heat is wasted in penetrating any heat insulating wall of coke. The latent heat 55 released by the mercury in its condensation is

therefore practically all utilized in doing useful work. The cracking operation is therefore conducted with a high degree of economy and efficiency.

Inasmuch as the tubes are never subjected to high heat, they never burn and there is no depreciation of equipment.

To the extent that clogging of the tubes is avoided, the system can be operated continuously for a relatively long time, which is another factor that makes for economy.

The rate of heat transfer to the oil may be accurately controlled.

No part of the oil is heated above the maximum cracking temperature desired.

The oil may be heated through a cracking range, say of 300° F., while the temperature difference between the heating medium and the oil at any stage of the heating, may be very much less than this range.

The primary heating medium (e. g. furnace gases) is utilized to first heat the secondary heating medium (the mercury) that directly furnishes the heat required for cracking, and to next preheat the oil to about the lower limit of the temperature range for cracking, thereby providing for the most economical utilization of the heat of the primary heating medium.

While mercury is preferred as the secondary heating agent, it is possible to substitute other vaporizable metals, such as cadmium and zinc.

We do not herein claim that part of the described process which involves, in addition to the maintenance of a tube temperature below the zone of coke-forming temperatures, the discovery that the solid matter that so deposits in the tube is a soluble solid whose removal may be effected by other than mechanical means. Such invention forms the subject matter of a separate application filed February 10, 1926, Serial No. 87,244, by J. Howard Pew.

What we claim is:

1. The process of cracking mineral oil which comprises heating a body of liquid mercury under an absolute pressure required to produce mercury vapor at a temperature above that at which substantial cracking of the oil 116 will occur, but below that required to form any substantial amount of coke, establishing a flowing stream of oil of great length and small thickness at a temperature below that of the mercury vapor and flowing the mercury vapor into a confined space surrounding the flowing elongated stream of oil and into heat exchange relation with the oil to effect condensation of mercury vapor and such transfer of its latent heat to the oil as will decompose higher boiling constituents thereof into lower boiling products, returning the condensed mercury to the body of liquid mercury, and continuously removing the oil from the locus of heat exchange.

2. The process of cracking mineral oil which comprises heating a body of liquid mercury under an absolute pressure required to produce mercury vapor at a temperature 5 above that at which substantial cracking of the oil will occur, establishing a continuously flowing stream of oil of great length and small thickness at a temperature below that of the mercury vapor and flowing the mercury vapor into a confined space surrounding the flowing elongated stream of oil and into heat exchange relation to effect condensation of mercury vapor and such transfer of its latent heat to the oil as will decompose 10 higher boiling constituents thereof into lower boiling products, imposing such superatmospheric pressure on the oil as will maintain it during its decomposition mainly in liquid phase, returning the condensed mercury to 15 the body of liquid mercury, and continuously removing the oil from the locus of heat exchange.

3. The process of cracking mineral oil which comprises subjecting the oil to the 20 process set forth in claim 2 followed by subjecting the partially decomposed oil to another treatment which is the same as that set forth in claim 2 but in which the mercury condensation temperature is higher than that 25 in the first treatment.

4. The process of cracking mineral oil which comprises flowing a stream of oil successively through a series of cracking zones, flowing mercury vapor from a common source 30 independently into a space in each zone surrounding the oil stream and into heat exchange relation with the oil therein and effecting in each space condensation of mercury vapor and transfer of its latent heat to the oil to the degree required to effect substantial cracking of the oil, maintaining progressively higher mercury condensation temperatures in the successive cracking zones, returning the condensed mercury from each 40 cracking zone to the body of liquid mercury, and continuously removing the oil from the last cracking zone.

5. The process of cracking mineral oil which comprises flowing a stream of oil successively through a series of cracking zones, heating a body of liquid mercury under the superatmospheric pressure required to vaporize the mercury at a temperature materially above that required to crack the oil but not 50 more than about 100° F. in excess of the highest temperature to which it is desired to heat the oil, flowing such vapor into the several cracking zones around the oil stream and in heat exchange relation with the oil and effecting in each space condensation of mercury vapor and such transfer of its latent heat to the oil as will decompose higher boiling constituents into lower boiling products,

and independently regulating the temperature of condensation and the rate of heat transfer in each zone by independently regulating the rate of flow of the vapor into the several zones so as establish therein mercury condensation temperatures progressively decreasing from the last heating zone to the first 65 heating zone, returning the condensed mercury to the body of liquid mercury, and continuously removing the oil from the last cracking zone.

6. The process of cracking mineral oil which comprises heating a body of liquid mercury under an absolute pressure required to produce mercury vapor at a temperature above that at which substantial cracking of the oil will occur, establishing a continuously 70 flowing stream of oil at a temperature below that of the mercury vapor and flowing said stream and the mercury vapor into heat exchange relation to effect condensation of mercury vapor and such transfer of its latent heat 75 to the oil as will decompose higher boiling constituents thereof into lower boiling products, maintaining at the locus of heat exchange a predetermined absolute mercury vapor pressure less than that at the locus of mercury 80 vapor generation by restricting the rate of flow of the mercury vapor to the locus of heat exchange, returning the condensed mercury to the body of liquid mercury and continuously removing the oil from the locus of 85 heat exchange.

7. The process of cracking mineral oil which comprises heating a body of liquid mercury under an absolute pressure required to produce mercury vapor at a temperature 90 above that at which substantial cracking of the oil will occur, establishing a continuously flowing stream of oil at a temperature below that of the mercury vapor and flowing said stream and the mercury vapor into heat exchange relation to effect condensation of mercury vapor and such transfer of its latent heat to the oil as will decompose higher boiling constituents thereof into lower boiling products, providing an independent path for 95 the flow of mercury from the locus of generation of mercury vapor back to the body of liquid mercury, controlling the maximum pressure of the mercury vapor in the flow line by opposing a predetermined resistance 100 to flow of mercury through said path, continuously removing the oil from the locus of heat exchange and independently controlling the flow of mercury vapor from the flow line to the locus of heat exchange.

In testimony of which invention, we have hereunto set our hands, at Philadelphia, Pennsylvania, on this 23rd day of January, 1926.

ARTHUR E. PEW, JR.
HENRY THOMAS.
